UNITED STATES PATENT OFFICE.

VIOLA ROOT CAMERON, OF NEW YORK, N. Y.

FUEL-CHARGE-TREATING DEVICE.

Application filed October 12, 1922. Serial No. 524,216.

To all whom it may concern:

Be it known that I, VIOLA Root CAMERON, a citizen of the United States, residing at New York, in the county of New York 5 and State of New York, have invented new and useful Improvements in Fuel-Charge-Treating Devices, of which the following is a specification.

This invention relates to gas saving devices for internal combustion engines, and pertains particularly to devices for breaking up and mixing combustible charges of fuel and air.

This invention is an improvement on the 15 type of gas saving device described in the patent to Lampert 1,192,435, issued July 25, 1916, which patent provides for an article to be inserted between a carbureter and the intake ports of an engine, the device including a metal plate member having a coiled spring cone mounted over an opening in the plate member, and having its base coil fixed to the plate member, the remainder of the cone being unattached and free to vibrate. 25 In the Lampert device, the plate is of solid material; has the general contour of a gasket; and is used between adjacent flanges of pipe ends. The metal wall of the opening in the Lampert device is provided with an annular groove to receive and hold, by the expansive spring action, the largest or base coil of the spring cone.

The general object of the present invention is to improve on the Lampert type of device, and at the same time, retain the advantageous features of the freely vibratile spring cone.

One of the features of the invention relates to the improved means for so securing 40 the base coil of the spring wire to the supporting plate that the coil cannot be loosened or separated accidentally from the supporting plate, due to the vibrations of the spring or the jolting or vibration of the 45 engine.

Another feature is the combination of the spiral spring with the standard asbestos copper gasket, supplemented and modified by the particular fastening means for holding 50 the spring over the gasket opening.

Another feature is directed to the particular shape and mounting of the spiral spring cone, which may be compressed to occupy the space of the thickness of the gasket or 55 plate in the opening of which it is mounted.

This design makes it possible to insert the plate or gasket and spring sidewise into position between adjacent pipe ends without necessitating the wide separation of the connection, it being merely necessary to loosen 60 the connection sufficiently wide to insert the thickness of the plate or gasket. After such insertion, the spring cone is then free to assume its normal conical shape, and to serve in breaking up the incoming charge of the 65 fuel mixture. This feature is particularly important because of the ease by which the device may be installed. By using an asbestos copper gasket of ordinary thickness, and having the cross-sectional diameter of 70 the material of the spring no greater than the thickness of the gasket, the device may readily be inserted in any engine intake line without requiring modification of the engine 75 parts.

The device of the present invention may be inserted at any connection between the carbureter and the inlet ports. Satisfactory locations have been at the engine and at the carbureter ends of the intake manifold. The 80 apex of the cone may extend in either direction, according to convenience, provided it does not interfere with the engine parts.

The above and other features and advantages of the device of the invention will be 85 described and claimed in the following specification and claims, and illustrated in the accompanying drawing, in which:

Fig. 1 represents a sectional view through one form of the device, showing the conical 90 spring having its lower and largest coil held between opposite metal faces of an asbestos copper gasket, the intermediate asbestos portion being spaced back from the central opening to provide space for the reception 95 of the spring;

Fig. 2 shows a sectional view through a 100 form of the device, including an asbestos copper gasket, in which an annular ring holds the lower and largest coil of the spring in its position adjacent the wall of the opening through the gasket. In this form, the ring is a separate member and extends from one face of the gasket through the opening and alongside of the opposite gasket face; 105

Fig. 3 represents a top plan view of the gasket and retaining ring, as shown in Fig. 2, but with the spring removed;

Fig. 4 shows, in section, the gasket illustrated in Fig. 2, but with the conical spring 110

compressed into the plane of the gasket, illustrating the compressed position in which the device is adapted to be inserted between adjacent pipe and flanges;

8 Fig. 5 represents a top plan view of the conical spiral spring removed from the gasket and retaining member;

Fig. 6 represents a sectional view of a modified form of the combined asbestos 10 copper gasket and spring, in which one face of the metal portion of the asbestos copper gasket projects centrally and then axially through the opening and is recurved about the largest coil of the spring and alongside 15 of the opposite face of the gasket;

Fig. 7 represents, in section, a modification of the form illustrated in Fig. 6, the spring retaining means being formed of a plurality of eyelets, struck up from the 20 material of one face; and

Fig. 8 represents a top plan view of the asbestos copper gasket, shown in Fig. 7, illustrating one of the eyelets projecting centrally prior to being recurved about the 25 largest coil of the spring member.

Referring in detail to the various figures of the drawings, like numerals refer to like parts in the different figures.

1 is a spiral spring member formed in the 20 shape of a cone, and so designed that it may be compressed to a plane having the thickness of a cross-section of the material of the wire, as illustrated in Fig. 4. The apex of the cone is indicated at 1^a. The base of the cone is formed by the largest coil or turn of the spring wire and is indicated at 1^b. 2 represents a gasket member or plate upon which the spring 1 is mounted, and which serves to hold the spring in its operative 40 position when installed in the intake line of an internal combustion engine. 3 is a central opening in the member 2, and 4 indicates end slots or openings for the reception of fastening bolts or studs by which the member 2 and its adjacent pipe connections are 45 secured together. The spring 1 is held in its mounted position with the axis of the cone in line with the axial center of the opening 3 and accordingly, the largest coil 1^b is held 50 adjacent to the wall of the opening 3, or actually in the same plane with the wall of the opening.

The invention provides several different specific constructions for securely holding 55 the coil 1^b in its position about the opening 3. In the sectional views of the drawing, the upper face of the gasket member is indicated at 2^a and the lower face is indicated at 2^b, and the asbestos intermediate portion of the 60 gasket is indicated at 2^c. In the form illustrated in Fig. 1, the asbestos portion 2^c is cut back away from the central opening, thus providing an annular space between the faces 2^a and 2^b, as indicated at 5. The largest 65 coil of the conical spring 1 is shown held in

this annular space by its spring action, which tends to expand the lower coil 1^b against the material 2^c. Thus, the spring is held by the material 2^c laterally, and by the opposite metal material 2^a and 2^b on the top and bottom.

In the form illustrated in Fig. 2, a separate element 6 is illustrated, as engaging the under face of the gasket, passing through the opening and then being recurved along 75 the upper face. This particular holding means is thus formed as a ring having an annular groove, the side walls of which enclose the largest coil 1^b of the spring cone, and also that portion of the gasket metal 80 faces 2^a and 2^b next adjacent the central opening 3. In both Figs. 2 and 3, an opening 7 will be seen, through which the upwardly extending spring projects. The opening 7 is preferably elongated in order to 85 prevent undue distortion of the curvature of the spiral spring. It is desirable also that the opening 7 extend through the thickness of the member 6, sufficiently deeply so that the coil of the spring projecting through 90 the opening may be compressed to the plane of the gasket, as in Fig. 4.

In the modification illustrated in Fig. 6, the retaining element 6 is formed by an extension of the under face of the copper portion of the gasket, which will be seen as extending centrally, thence through the opening, and thence alongside of the opposite face 2^a. This arrangement is substantially 100 the same in effect as the form illustrated in Fig. 2, except that the part 6 is formed as a continuation of one gasket face instead of being a separate member, as in 2.

In the modification illustrated in Figs. 7 and 8, the under face of the copper portion 105 of the gasket is extended inwardly to form a plurality of eyelets 8 adapted to be curved upwardly through the opening 3 and thence alongside of the opposite face of the gasket. This arrangement is substantially similar 110 to the arrangement illustrated in Fig. 6, except that the eyelets are formed separately instead of as one continuous portion, as illustrated in Fig. 6. In Fig. 8, the length of one eyelet member is shown as fully extended 115 centrally, and prior to the recurving of it into the eyelet shape.

In the arrangement shown in Fig. 1, the outward spring expansive action of the larger coil 1^b serves to hold it in the annular space between the opposite faces of the copper portion of the gasket. In the other views of the drawing, it is intended that the end of the larger coil of the spring cone be inserted 120 into the opening 7 and the coil and gasket rotated with respect to each other, so as to thread the largest coil 1^b into and around through the space provided by the fastening member 6, the side faces 2^a and 2^b of the gasket and the asbestos material 2^c. In the 125 130

form shown in Figs. 7 and 8, the eyelet members may be bent up and recurved around the largest coil 1^b of the wire, or the end of the largest coil may be threaded 5 through the plurality of eyelets in substantially the same manner as provided for in Figs. 2, 3, 4 and 6.

For the insertion of the combined spring and gasket into position in an internal combustion engine, the invention contemplates 10 the use of any necessary device, such as a pair of pliers, by which the spring may be compressed to the thickness of the material of the gasket by the same movement and by 15 the same position of the implement which the operator uses in holding the gasket. If the place of installation be readily accessible, and the spring readily compressible, the operator may use his fingers in compressing 20 the spring and slipping the device sidewise, or edgewise, in between the adjacent pipe ends.

The curvature of the spirals of the spring should be so arranged that a line drawn 25 through the material of the spring at any point and parallel to the axis of the cone will not pass through the material of the next adjacent turn or coil of the spring, or any other portion of the spring. This description 30 is presented as one way of stating that the conical spring may be compressed to a given plane without distorting any of the turns or coils of the spring in order to assume the plane position.

Claims specific to Figs. 6, 7 and 8 are 35 presented in my divisional application, Serial 601,282, filed November 16, 1922. Claims specific to Fig. 4 are presented in my divisional application Serial 601,283, filed 40 November 16, 1922.

I claim:

1. In a device of the character described, a plate member having an opening therethrough, a coiled spring cone having the 45 base thereof positioned in said opening and freely vibratile from the base to and including the apex of the cone, and fastening means supported by said plate member and engaging the base portion of said cone on 50 the side thereof opposite to the encircling

wall of said opening and holding said cone in axial alignment with said opening.

2. In a device of the character described, a plate member having an opening therethrough, a coiled spring positioned in line 55 with said opening, fastening means supported by said plate member substantially encircling the coil of said spring next adjacent the wall of said opening and engaging said coil on the axial side thereof, said spring being freely vibratile from the supported portion thereof next adjacent the wall of said opening to and including the opposite end of said spring.

3. In a device of the character described, 60 a gasket comprising opposite outer metal faces and an intermediate material therebetween and having an opening through the thickness of the gasket, a coiled spring having the largest coil thereof fitted concentric 65 with the wall of said opening, and a recurved ring member extending from a position alongside of one face of said gasket, thence axially of said largest coil and thence alongside of the opposite face of said 70 gasket, providing an outer annular groove the side walls of which embrace said largest coil and the adjacent portions of said opposite gasket faces, said spring being freely 75 vibratile from the supported portion thereof next adjacent the wall of said opening to 80 and including the opposite end of said spring.

4. In a device of the character described, 85 a gasket comprising opposite outer metal faces and an intermediate material therebetween and having an opening through the thickness of the gasket, a coiled spring having the largest coil thereof fitted concentric with the wall of said opening, and a separate 90 ring member secured to the metal portion of the gasket and engaging the axial side of said largest coil to hold it to the wall of said opening, said spring being freely vibratile from the supported portion thereof 95 next adjacent the wall of said opening to and including the opposite end of said spring.

In testimony whereof I affix my signature.
VIOLA ROOT CAMERON.
